UNITED STATES PATENT OFFICE.

HERBERT ALFRED HUMPHREY, OF LONDON, AND WILLIAM JOSEPH RUSDELL, OF DUDLEY, ENGLAND, ASSIGNEES TO HUMPHREY GAS PUMP COMPANY, A CORPORATION OF NEW YORK.

UTILIZING AN EXPANSIVE FORCE.

1,271,712.

Specification of Letters Patent.

Patented July 9, 1918.

Application filed May 16, 1912. Serial No. 697,792.

To all whom it may concern:

Be it known that we, HERBERT ALFRED HUMPHREY, a subject of the King of Great Britain, residing in London, England, and 5 WILLIAM JOSEPH RUSDELL, a subject of the King of Great Britain, residing in Dudley, Worcester, England, have invented a new and useful Improvement in Utilizing an Expansive Force, of which the following is a 10 specification.

Our invention relates to improvements in utilizing an expansive force. Our object is to utilize the expansive force of a compressed ignited combustible charge to compress and deliver an elastic fluid. The invention comprises improved means for utilizing the momentum of a reciprocating solid body, actuated by said expansive force, in compressing the elastic fluid, in delivering 15 20 said compressed elastic fluid, also in introducing fresh combustible charges. The energy stored by said reciprocating body or bodies may be utilized for controlling said reciprocations.

25 Our invention also comprises the use of a solid body or solid bodies linked together in connection with liquid body or bodies, which are reciprocated together to compress elastic fluid or otherwise store energy, which stored 30 energy may be utilized in a number of ways including the controlling or affecting the efficiency of operation of the apparatus.

Referring to the drawings, which illustrate diagrammatically merely by way of 35 example, apparatus suitable for effecting or realizing our invention—

Figure 1 is a vertical section of a simple form of compressor having a combustion chamber, a play pipe and a compression 40 chamber with suitable inlets and exits and a solid piston adapted to reciprocate in the play pipe.

Fig. 1^a is a similar view showing the compression chamber end of the apparatus with 45 a supplemental connected piston and a second compression chamber.

Fig. 2 is a similar view of a modified form showing pistons of different diameters.

Fig. 3 is a similar view showing second 50 piston disconnected.

Fig. 3^a is a similar view showing a dashpot control for the disconnected piston.

Fig. 4 is a similar view with modifications

showing second piston provided with a 55 plunger.

Fig. 5 is a similar view with modifications showing a liquid body coöperating with the solid piston.

Fig. 5^a is a detail on an enlarged scale 60 showing valve 21.

Fig. 6 is a similar view with modifications, showing means for compressing the elastic cushion in two stages.

Fig. 7 is a similar view showing modifications of apparatus shown in Fig. 6. 65

Fig. 8 is a similar view showing apparatus suitable for exhausting elastic fluid or pumping elastic fluid from a lower pressure than atmosphere to atmospheric pressure.

Similar numerals refer to similar parts 70 throughout the several views.

Fig. 1 represents a very simple form of an internal combustion pump in which 1 is the combustion chamber and 2 a solid reciprocating mass, in this case moving as a piston 75 in a cylinder or play pipe 3 and acting directly upon elastic fluid to be compressed in chamber 9. 5 is the inlet for elastic fluid communicating with the supply valve 6 and port 10. 7 is the outlet through which the 80 compressed elastic fluid is delivered, communicating with the delivery valve 8 and port 11. The ports 10 and 11 are so arranged that when the piston 2 has moved a certain distance to the right the ports are covered 85 by the piston and the further delivery of compressed elastic fluid prevented. The operation is as follows:—On ignition of the compressed combustible charge in the combustion chamber 1, piston 2 is forced toward 90 the right and acquires momentum, and elastic fluid which fills the space to the right of the piston is first compressed to the pressure at which the delivery valve 8 opens and is then delivered. Depending chiefly upon 95 the distance of the port 11 from the end 4 of piston 2 when ignition occurred, and also upon the pressure of delivery and the amount of energy produced by the expansion of the combustible charge, the piston 2 will 100 come to rest either before the port 11 is covered or after this has happened; in the latter case an elastic cushion will be trapped in the space to the right of port 11 and further compressed by the continued movement 105 of the piston. In any case, the space to the

right of the piston when it comes to rest will contain compressed elastic fluid which, acting as an elastic cushion, will cause the piston to return to compress a fresh combustible charge and also it may be to expel products of combustion. The fresh charge may have been drawn into the combustion chamber during the outstroke or may be introduced under pressure during either the outstroke 10 or the instroke in any known manner. Since, owing to its kinetic energy, the piston continues to move after the elastic fluid in chamber 9 has expanded to the pressure of the elastic fluid supply, fresh elastic fluid is 15 drawn past valve 6 into chamber 9. Piston 2 is brought to rest by the compression of the fresh combustible charge in chamber 1 and ignition occurs to start a fresh cycle. The port 10 may be placed opposite port 11 so 20 that the piston passes both ports together and this insures an elastic cushion always being retained to the right of piston 2 under all conditions. It will be noticed that providing the piston 2 does not pass port 11 for 25 a given pressure at which elastic fluid is delivered, the shorter the stroke of the piston to the right, the greater will be the amount of energy stored by the elastic fluid in chamber 9. Should the piston pass port 11 the 30 longer the outward stroke of the piston after this period, the greater will be the amount of energy stored in chamber 9. For many reasons it is advisable that the energy stored for effecting or assisting the return stroke 35 shall remain constant within desired limits and Fig. 1^a shows an arrangement for this purpose in which a second piston 2^a working in a cylinder 3^a is connected with piston 2 by a rod 12 which passes through the cylinder end 13 fitted with suitable glands. Piston 2 as in Fig. 1 works in a cylinder 3, and to the right of this piston is the chamber 9. Valves 6 and 8 correspond in functions 40 with those in Fig. 1 indicated by the same numbers; like valves 6^a and 8^a communicating with ports 10^a and 11^a respectively, are provided in cylinder 3^a. When piston 2^a moves to the left elastic fluid may be drawn in behind it through valve 6^a, and during the 45 outward stroke of the piston elastic fluid may be compressed to the right of piston 2^a and some of it delivered through valve 8^a in a similar manner to the elastic fluid which is compressed and delivered with respect to 50 chamber 9. Valve 8 is situated close to the end 13 of chamber 9 whereas valve 8^a is shown at a considerable distance from the end 13^a of chamber 9^a. Thus on the outward stroke piston 2^a will pass port 11^a before 55 piston 2 reaches port 11 and as the pistons 2 and 2^a move farther to the right the energy stored in the compressed elastic fluid in chamber 9 will be decreasing while that stored in chamber 9^a will be increasing, and 60 piston 2 reaches port 11 and as the pistons 2 and 2^a move farther to the right the energy stored in the compressed elastic fluid in chamber 9 will be decreasing while that stored in chamber 9^a will be increasing, and 65 the total energy stored in the two chambers

9 and 9^a may therefore remain approximately constant within certain limits. Pistons 2, 2^a may each pump a portion of the same elastic fluid or they may pump different elastic fluids and such elastic fluids may 70 differ in initial pressure or delivery pressure or both. The pistons may also differ in diameter. Under certain circumstances valves 6^a, 8^a, or 6 and 8 may be dispensed with, in which case the respective piston 75 merely closes the respective ports; in such cases during the first part of the outstroke the pressure will not increase in that cylinder where the valves are omitted until the piston closes the ports and modified working 80 will result. Ports 14 are shown to the left of piston 2^a, such that the pressure will remain approximately constant in the cylinder to the left of piston 2^a until during the instroke the ports are closed by the piston. 85 A cushion of elastic fluid will then be trapped between piston 2^a and cylinder end 13 to store energy and to limit the motion of the piston to the left.

Fig. 2 shows an arrangement similar to 90 Fig. 1^a in which a piston 2^a is of larger diameter than the piston 2. These pistons work in their respective cylinders and may close the ports in both cylinders at the same time or it may be that the ports in the 95 smaller cylinder are closed either before or after the ports in the larger cylinder, the positions of which are selected, according to the desired pressures and manner of working. In Fig. 2 no valves are shown in 100 connection with ports 10 and 11, in which case elastic fluid will not be delivered under pressure by piston 2. If valves corresponding with 6 and 8 in Fig. 1 are added, elastic fluid may be taken in through port 10 and delivered through port 11. The elastic fluid compressed in the large cylinder may be delivered first to a reservoir and then to the smaller cylinder to be further compressed, which arrangement will constitute 110 a 2-stage compressor.

In Fig. 3 an enlarged extension of the cylinder is provided fitted with a piston 15 shown in its extreme position to the left, further movement to the left being prevented by the shoulder due to the change of diameter, this shoulder being preferably provided with a resilient buffer not shown. The space to the right of piston 15 contains elastic fluid under sufficient pressure to prevent 120 movement of the piston to the right until the pressure to the left of the piston rises above the delivery pressure. After ignition and during the outstroke the movement of the piston 2 first compresses elastic fluid to the 125 right of piston 2 and then delivers part of it past valve 8. If the piston 2 should pass the delivery port 11 the pressure in space 9 will rise above the delivery pressure and then this pressure exerted upon piston 15 130

may cause the latter to move to the right as piston 2 moves in this direction. By this arrangement the ports 11 may be placed quite close to the piston 15 and so that what 5 is technically known as clearance space may be quite small and the output from the compressor increased. After piston 2 has passed ports 11 and when both pistons move to the right the pressure of the elastic fluid contained 10 between them only increases as the pressure of the elastic fluid to the right of piston 15 increases, and as the initial volume of the elastic fluid to the right of piston 15 may be considerable the rise in pressure can 15 be small although the requisite amount of energy is stored for the return stroke. Instead of providing a stop to arrest the motion of piston 15 to the left, as shown in Fig. 3, such motion may be arrested by a small 20 piston 17 (Fig. 3^a) working in a cylinder containing elastic fluid or liquid and acting as a dash-pot. This arrangement has the advantage of affording a ready means of controlling the position in which piston 15 is arrested and thus altering the clearance space.

Fig. 4 shows an arrangement in which a return stroke is effected or assisted by the pressure of elastic fluid which has been delivered 30 past the delivery valve 8. The outlet pipe 7 communicates with a chamber in which works a ram 17. On the outward stroke therefore work is done by compressing and delivering elastic fluid from chamber 9 and by forcing the ram 17 to the right against the delivery pressure of the elastic fluid acting upon it. The inward stroke occurs under the influence of the pressure of delivered elastic fluid upon ram 17 acting in 35 conjunction with the expanding elastic fluid in chamber 9. In such cases the cushion which is trapped when piston 2 passes port 11 need only act as a cushion to insure safe working and may therefore be of smaller 40 size than when it has to store the whole of the energy for the return stroke. Part of the reciprocating mass is shown in Fig. 4 as liquid retained between piston 2 and piston 18. It is not necessary that piston 18 should 45 be of the same diameter as piston 2, and the pistons may be made of convenient sizes better to fulfil their respective functions. By providing an additional cylinder 19 into which the ram 17 will work after having 50 completed a desired portion of its outstroke, an additional elastic cushion can be trapped in the cylinder so soon as the ram 17 enters it. In such case the ports 11 may be situated closer still to the end 13 of chamber 9 55 and the volume of clearance therein still further reduced. In extreme cases both valves 6 and 8 may be placed in the cylinder end 13. In Fig. 5 liquid is shown interposed between the elastic fluid and the solid piston. On the outward stroke the motion of

the piston 2 is communicated to the mass of liquid in space 20 and elastic fluid is taken in and delivered from the chamber 9 above the liquid. 6 represents the valve for the intake of fresh elastic fluid and 8 is the non-return valve to prevent the return of elastic fluid to chamber 9. 21 is a valve which is normally open under the action of a spring or its equivalent but adapted to be closed when liquid attempts to pass it. Thus, on 70 the outward stroke the liquid will first compress elastic fluid in chamber 9 and then deliver elastic fluid until valve 21 is closed by liquid. A cushion of elastic fluid will then be trapped above the liquid and further compressed by the continued outward motion of piston 2. In other respects the action of the apparatus is similar to that described with reference to Fig. 4 in that the pressure of elastic fluid delivered acts upon a ram 17 to 75 supply energy to assist the return of piston 2 toward the combustion chamber. 9^c represents a number of plates, preferably perforated, or wires; or any other known contrivance for retaining liquid so that a large 80 surface may be provided in contact with the elastic fluid compressed for the purpose of cooling it. By this device the compression may be more nearly isothermal.

Fig. 6 shows an arrangement suitable for 95 compressing the elastic fluid in two stages. Elastic fluid is first compressed and delivered into a receiver 22, here shown provided with plates of the kind aforesaid. This receiver communicates with a cylinder 100 in which works a ram 23 connected with or attached to piston 2 and so that the pressure of the delivered elastic fluid in 22 assists the return stroke. On an outward stroke elastic fluid which has entered the cylinder 105 behind the ram 23 on an inward stroke is further compressed and delivered through the non-return valve 24. Valve 25 is a non-return valve which prevents elastic fluid which has entered the small cylinder in 110 which ram 23 works from returning to the receiver.

The arrangement shown in Fig. 7 works similarly to the last mentioned case, but a piston 23 is substituted for the ram 23 of 115 Fig. 6; also instead of pistons 2 and 23 compressing the elastic fluid by direct contact therewith, masses of liquid are interposed between the piston and the elastic fluid. Also, the gases in combustion chamber 1 do not act directly upon piston 2, liquid being interposed between them, and the arrangement of valves and the operation thereof may be as described in my previous specifications. If desired, liquid need only 120 be interposed between one of the pistons and the elastic fluid compressed.

In the arrangements shown by Figs. 6 and 7 respectively, by arranging that delivery of elastic fluid from the first com- 130

pressor chamber shall cease at a different time from the delivery from the other compressor chamber, an approximately constant amount of energy may be stored for effecting the return stroke irrespective of the length of stroke of the solid pistons in a similar manner to that described with reference to Fig. 1^a.

Fig. 8 represents an arrangement suitable for exhausting elastic fluid or pumping elastic fluid from a lower pressure than atmospheric pressure to atmospheric pressure. 1 is the combustion chamber and the out-stroke of the piston 2 is toward the left. A piston 37 connected with piston 2 by rod 38 works in a cylinder fitted with valves 6 and 8 for the admission and delivery respectively of elastic fluid, which is assumed to be initially at a pressure lower than atmospheric. During the outward stroke of piston 2, fresh elastic fluid is drawn in to the compressor cylinder past valve 6. It is assumed that the space to the left of piston 37 is open to the atmosphere, and thus as piston 2 moves to the left work is done against the excess of pressure to the left of piston 37 over that existing to the right, and when the work done on piston 2 by the expanding gases equals that performed by piston 37 against the difference in pressure just referred to, together with frictional losses, the connected pistons come to rest. The inward stroke now begins and elastic fluid which has been taken in past valve 6 becomes compressed and delivered past valve 8. Also the combustible charge which has meanwhile been introduced into chamber 1 is compressed ready for ignition. By suitably placing the intake and delivery ports of the compressor chamber, it may be arranged that the cushion of elastic fluid may be further compressed after piston 37 passes these ports during its stroke to the right. If the left hand end of the compressor cylinder is closed the elastic cushion may be constituted therein to store energy on the outstroke for assisting the return of the pistons; or this end of the cylinder may be fitted with valves 6^a and 8^a for taking in, compressing and delivering elastic fluid. Another piston 39 may be provided and connected with pistons 37 and 2 by rod 40. The right hand end of the cylinder in which this piston works communicates with a reservoir 22 which is also in communication with valve 6. It is assumed for the moment that the spaces to the left of pistons 39 and 37 are both open to the atmosphere and that only valve 6 is in communication with reservoir 22. Now during the outward stroke of the pistons there will be additional work done due to the difference of pressure on the two sides of piston 39 which on the inward stroke becomes available for aiding delivery of elas-

tic fluid from the space to the right of piston 37 and the work of compressing a fresh combustible charge in 1. By fitting valves 6^b and 8^b to the cylinder in which piston 39 works, 6^b being connected with reservoir 22, 70 elastic fluid may be taken into the cylinder from reservoir 22 during the instroke and compressed and delivered on the outstroke.

By providing suitable connections it may be arranged that the elastic fluid is pumped 75 in two stages, thus the first stage may occur either on the right or left hand side of piston 37 or on both sides, and the final stage on the left hand side of piston 39.

In our copending application filed May 80 11, 1912, Serial No. 696,639, there have been described arrangements whereby the working 85 of the apparatus may be controlled by varying lengths of stroke, the velocities of liquid, and also safety devices. Thus, abnormal movements of the reciprocating masses have been utilized to control the apparatus so that it is once more brought back 90 to its normal conditions of working. Also, should pressures in certain parts of the apparatus fail to be maintained then the ignition circuit may be opened or an exhaust valve may be opened. These arrangements 95 may be directly applied to the present invention.

In the specification just referred to it has been shown how the reciprocating masses may be linked together so that the various pistons need not be co-axial and also how by altering the effective radius of oscillation 100 of a reciprocating mass the rate of working of the apparatus may be controlled. Such constructions are equally applicable to the present invention. As the arrangements work in a precisely similar manner it is not 105 necessary to again describe them in this specification. Again it was explained in the said specification that the method of governing by inertia may be applied. This is 110 equally applicable to the present invention. For example a part moved by the reciprocating masses may carry a displaceable part, the inertia of which determines the degree of displacement and this latter may be used 115 to operate suitable controlling devices. In another mode of governing, a device for wasting energy may be used which comes 120 into operation should the amount of energy developed on a power stroke exceed a desired amount. For example, the exhaust of the burnt products may be throttled so that 125 energy is wasted in driving out such burnt products from the combustion chamber or some of the combustible mixture which has been compressed for a fresh ignition can be allowed to escape before ignition, thus reducing the available energy; again the exhaust may be opened at any stage of the expansion. The exhaust valve may also be held closed during the power stroke so that 130

burnt products are expanded below atmospheric pressure, and in such case the energy 5 may be wasted by opening the valve at the end of the stroke or, if desired, the valve may only be opened when on the return stroke atmospheric pressure is again reached.

It is sometimes desirable that positively measured charges should be employed, and then the control device may operate on the 10 charge measuring device so as to vary the amount of combustible mixture. Suitable charge measuring devices have been described in our previous specification.

Where part of the reciprocating masses 15 consists of liquid the quantity of this liquid may be increased or decreased so as to alter the total weight of the reciprocating masses and a control mechanism may actuate a device for determining the quantity of reciprocating liquid which exists in the apparatus at any particular time and for varying such quantity.

What we claim is:—

1. An elastic fluid pump operating without 25 a fly wheel, which comprises a power chamber having inlet and discharge valves, a play pipe in operative relationship therewith containing space for a reciprocating piston, means forming a space in advance of 30 the piston for an elastic fluid with inlet and discharge valves, a piston adapted to be actuated in one direction, by the energy of a primary actuating medium to compress and deliver elastic fluid, and in the opposite direction, the return stroke, by elastic fluid pressure, and means comprising piston, cylinder, and discharge port suitably located with respect to the compression space beyond, whereby the total energy stored in the 35 elastic fluid utilized for causing the return stroke is maintained approximately constant.

2. An elastic fluid pump operating with-

out a fly wheel which comprises a power chamber having inlet and discharge valves, 45 a play pipe in operative relationship therewith containing space for a reciprocating piston, means forming a space in advance of the piston for an elastic fluid with inlet and discharge valves, a piston adapted to be 50 actuated in one direction, by the energy of a primary actuating medium to compress and deliver elastic fluid, and in the opposite direction, the return stroke, by elastic fluid pressure, and means forming and utilizing 55 an elastic cushion in a region other than that in which the primary actuating medium is delivered, for limiting the return stroke.

3. An elastic fluid pump operating without 60 a fly wheel, which comprises a power chamber having inlet and discharge valves, a play pipe in communication therewith containing a space for a reciprocating mass and for an elastic fluid cushion, a mass having sufficient weight to enable it to absorb energy 65 at the beginning of its movement and to give out energy toward the end thereof adapted to be actuated by a primary actuating medium acting directly thereon in said power chamber, and to act in coöperation 70 with the elastic fluid cushion, to reciprocate, inlet and discharge valves for elastic fluid operating to admit and discharge the elastic fluid into and from the space in advance of 75 said reciprocating mass, and means comprising piston, cylinder, and discharge port suitably located with respect to the compression space beyond whereby the total energy stored in the elastic fluid utilized for causing the return stroke is maintained approxi- 80 mately constant.
